Atty.

UNITED STATES PATENT OFFICE

ANTHONY HLAVAC, OF CHICAGO, ILLINOIS, ASSIGNOR TO EBER J. HUBBARD, OF
BERWYN, ILLINOIS

BOBBIN

Application filed May 16, 1929. Serial No. 363,648.

My invention relates to bobbins particularly adaptable for supporting silk or other thread or yarn which is to be steamed or dried.

One important object of the invention is to construct the bobbin entirely of sheet metal parts secured and interlocked together to produce a strong and durable structure.

Another important object is to provide improved arrangement of openings and circulatory passages for permitting intimate and voluminous contact of steam, air or heat with the bobbin contents so that the treatment can be rapidly and efficiently accomplished.

The above features and others are incorporated in the structure shown on the drawings in which

Fig. 1 is a side elevation of the bobbin,

Fig. 2 is an end elevation of the bobbin,

Fig. 3 is a plan view of an end disk,

Fig. 4 is a longitudinal section on plane

4—4, Fig. 2, and

Fig. 5 is a transverse section on plane 5—5,

Fig. 1.

The bobbin consists of the cylindrical hub or barrel 10, the end disks 11 and 12 and the spindle tube 13. The hub is formed from a piece of sheet metal with its longitudinal edges joined by the seam 14. As its ends the hub has the tongues 15 which extend through the openings 16 in the end disks and are deflected radially outwardly against the outer faces of the disks and lock the disks to the hub ends.

Each end disk has an axial opening 17 with recesses 18. The spindle tube 13 is formed of sheet metal and at its ends has tongues 19, the tube extending between the end disks and the tongues engaging in the recesses 18 and projecting primarily a distance beyond the disks as shown at the bottom of Fig. 4. These projecting tongue ends are then deflected radially outwardly against the outer faces of the end disks as shown in Fig. 4, and in Fig. 2, and thus rivet the end disks to the spindle tube. Any number of tongues may be used but I prefer to use two wide, diametrically opposite, tongues at each end of the tube, as shown.

To strengthen and stiffen the end disks

their peripheral sections are curled over to form rims or treads 20, and the inner section of each disk between the openings 16 and 17 is deflected outwardly to form an annular boss 21, the outer faces of the boss and rim being preferably in a common plane so that the bobbins may more readily stand on end and be stacked. The rim and boss will also protect the tongues 15 and 19 against wear and injury.

The tongues 15 engage against the outer edges of the openings 16, the openings being in greater part exposed to afford ample passageway for circulation into and through the interior of the barrel 10 of steam, air or heat with which the bobbin contents are to be subjected, and the barrel has the perforations 22 of sufficient number and so spaced that the bobbin contents will be well and uniformly exposed for the application and flow therethrough of the steam, air or heat, so that steaming or drying can be quickly and efficiently accomplished.

The tongues 15 may be spot welded or soldered to the end disks, and in order to prevent the bobbin contents from catching in the corners between the hub and disks, such corners are preferably filled with solder.

I do not desire to be limited to the exact structure shown as modifications may be made which would come within the scope of the invention.

I claim:

1. A bobbin of the class described comprising a sheet metal barrel having tongues at its ends, and end disks having each a circular row of openings for receiving at their outer ends the respective tongues, said tongues being bent radially outwardly against the outer faces of the disks to lock the disks to the barrel, the inner ends of said openings serving to connect the interior of the barrel with the outside, said barrel having perforations for exposing the bobbin contents to the interior of the barrel.

2. A bobbin of the class described comprising a cylindrical sheet metal barrel having tongues at its ends, sheet metal end disks having openings through which said tongues extend, said tongues being deflected against

the outer faces of said disks to lock the disks to the barrel, said openings being in greater part exposed to form passageways for the free flow of steam or air through the barrel,
5 said barrel having perforations for exposing the bobbin contents to the interior of the barrel, and a spindle tube extending axially through said barrel and interlocked with said end disks.

10 In witness whereof, I hereunto subscribe my name this 10th day of April, 1929.

ANTHONY HLAVAC.
